Anna Bauer,

By James R. Bowen,

Attorney.

UNITED STATES PATENT OFFICE.

ANNA BAUER, OF UNION, NEW JERSEY.

ROPE GRIP.

1,418,902.

Specification of Letters Patent. Patented June 6, 1922.

Application filed January 9, 1922. Serial No. 528,014.

To all whom it may concern:

Be it known that I, ANNA BAUER, a citizen of the United States, residing at the town of Union, in the county of Hudson and 5 State of New Jersey, have invented certain new and useful Improvements in Rope Grips, of which the following is a specification.

The present invention relates to improvements in rope grips in which two complementary members are mechanically associated together for relative movement and are adapted to be included in a clothes line or the like to effectually grip the rope and 15 maintain the line in a taut condition, while at the same time allowing of the convenient and ready slackening of the same.

It is the primary object of the invention to provide a device of this character in which 20 the actual gripping will occur between two portions of the rope itself, or in other words, a rope against rope grip is secured, eliminating the likelihood of cutting the rope as where metallic parts or teeth are made to 25 bite directly thereinto.

Other objects of the invention are to provide a simple, inexpensive device of a small character yet accomplishing the functions required of a device of this kind, and for 30 enabling the user to quickly attach the device to a clothes or other line and to manipulate it freely and with the greatest facility.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a side view of an improved rope grip constructed according to the present invention with parts of the line indicated, and with the device in gripping position;

Fig. 2 is a similar view with the grip released;

Fig. 3 is a central sectional view through the device in gripping position, and

Fig. 4 is a side view showing a slight modification.

Referring more particularly to the drawings, 1 and 2 designate generally a pair of companion members forming complements of each other and being adapted to receive 55 the end portions 3 and 4 respectively, of a clothes line, rope or the like. The member 1

is of a general ogee form, and provided with flanges 5 which are rounded with the base portion of the member and provide a trough extending longitudinally through the device 60 and of substantially the contour of the rope end 3, which is received therein in the manner indicated and having a pendant terminal part 6 which may be pulled upon to tighten the line or released to slacken the same. The 65 member 1 has its upper portion flaring away from the longitudinal median line of the device with its extremity lying substantially coincident with the axis of the line 3. The lower portion of the member 1 at the opposite side of the pivot point, hereinafter referred to, is shaped to provide an internal depression or socket 7 into which the rope 3 is forced as later explained. Both ends of the member 1 are open to receive the rope 75 and to permit it to slide freely therethrough. The flanges 5 are extended at their intermediate portion so as to overlap the flanged portion of the companion member 2 whereby a pivot pin 8 may be passed through 80 the overlapping parts of both members to pivotally secure them together and permit of their rocking between the two positions shown in Figs. 1 and 2.

The member 2 is provided with upper 85 flanges 9 forming a trough for the rope end 4, and having the outer end flaring in an opposite direction from the flaring of the adjacent end of the member 1. As shown more particularly in Fig. 3 an opening 10 is 90 made in the member 2 at its middle portion to the outside of the pivot 8 to permit of the rope 4 passing on the outside of the pivot which extends through the flange 11 forming continuations of and being slightly offset 95 inwardly with respect to, the upper flanged portion 9. The flanges 11 are open at their outer edge but are connected by a web 12 along their inner edges in which is made apertures 13 and 14 at opposite sides of a 100 truncated triangular or pyramidal projection 15 formed upon, or attached to the inner faces of the web 12 and lying opposite to, and cooperating with, the depression 7 in the companion member 1. The rope 4 extends through the apertures 13 and 14 with its intermediate portion extending about the removed apex of the projection 15, the rope being knotted as indicated at 16 to avoid its accidentally becoming unthreaded from the 110 device.

It will be seen that the rounded character

imparted by the construction described to the outer faces of the upper portions of the members affords appropriate grips for the hands of the user by which the device may 5 be collapsed manually as indicated in Fig. 2 when the release of the rope is required.

In the use of the device, the rope end 4 is threaded through the device in the manner best illustrated in Fig. 3 and is knotted at 10 its end to secure it in place. The other rope end 3 is placed loosely through the trough in the member 1 with its end pendant as represented. Inasmuch as the stretching of the line by reason of its weight and its tautness will tend to draw the ends 3 and 4 apart, the upper portions of the device above the pivot point 8 will respond to this influence which will attempt to spread such ends apart, and to consequently have quite the 15 opposite effect upon the lower ends which carry the depression and projection. The result is that the V-shaped portion of the rope 4 stretched over the projection 15 will force the rope end 3 into the depression 7 which will cause the rope to take a curvilinear form corresponding substantially to the curvature of the V-shaped portion of the rope 4 as aforesaid. The inner arcuate line of the rope portion 3 thus forced into the 20 depression will cause a compression of the fibers that will tend to form a firmer grip between these parts.

It will be appreciated that the gripping occurs between portions of one rope end and 35 the other and that no metallic surfaces are caused to bite into the rope at the meeting edges thereof, which of course have a slight relative movement or slippage between them, apt to result in the cutting of the rope parts. 40 No relative movement or slippage is encountered between the rope end 4 and the projection 15 and therefore no appreciable cutting occurs at this point.

When the line is to be slackened or further tightened the upper portions of the device are gripped and collapsed in the manner indicated in Fig. 2 which releases the grip and leaves the line end 3 to be drawn downwardly or slackened upwardly.

Referring more particularly to Fig. 4 a 50 device similar in both construction and operation is shown in which the member 1 is practically the same as above, the main difference lying in the companion member 17 which is elongated downwardly to a further extent and has its upper and lower portions lying at an acute angle with flanges 18 and 19 extending both above and below the center line and forming a trough to continuously receive the rope end 4 which passes 55 through the member in the lower end and is knotted as before. A projection 20 is formed upon the member 17 at the face of the trough and forces the rope downwardly at this 60 point forming a bight therein opposite the 65

depression of the companion member. The pivot point 8 in this case is above the elbow or angular meeting part of the divergent upper and lower parts of the member 17.

It will be appreciated that with this last mentioned form, as in the preferred case, all likelihood of injury to the rope or cord fibers is eliminated without at the same time sacrificing that firm grip which is necessary in connection with clothes lines and the like. 70 The device is found in practice to firmly secure the line, and at the same time to admit of its convenient and quick adjustment, and without doing the slightest injury to the rope itself. 75

I do not wish to be restricted to the size, form, and proportions of the various parts, and obviously changes might be made in the construction herein described without departing from the spirit of the invention. 80

What is claimed is:

1. An improved rope grip for lines comprising companion members mechanically associated for relative movement, said members receiving opposite ends of the rope 90 from the line for forcing such ends against one another to bind the two ends of the rope in the rope grip, said companion members being moved to grip the rope automatically by the tightening of the line. 95

2. A rope grip comprising a pair of companion members pivotally connected for relative rocking movement, and having channeled interior portions to receive opposite ends of a rope, the portions of the 100 members at one side of the pivot point being held apart automatically by the stretching action of the rope and the portions at the opposite side of the pivot point being by the same action moved together, the rope extending into the last named portion and being forced together upon opposite portions thereof to form a firm grip. 105

3. An improved rope grip comprising a pair of companion members pivoted together 110 with opposite ends of the rope passing on the inside faces thereof, one end of the rope being secured to one of the members while the other rope end is slideable through the companion member, said members having 115 between them a complementary trough and projection, the fixed end of the rope extending about the projection and adapted to force the loose end of the rope into the trough. 120

4. A rope grip comprising a pair of complementary members having flanges forming troughs to receive opposite ends of a rope, the flanges of one member being extended to overlap the flanges of the other member 125 and being pivoted at such overlapping portions, one of said members having a depression therein adapted to receive one end of the rope, the other member having a projection opposite the depression and adapted 130

to receive the other end portion of the rope whereby to provide a rope against rope binding action.

5. A rope grip comprising companion members pivoted together intermediate their ends, and having opposed troughs extending longitudinally thereof, and adapted to receive opposite end portions of a rope, the end portions of the members at one end of 10 the device being flared outwardly in opposite directions with their extremities lying

substantially coincident with the direction of the rope or line, the other end of one member having a trough therein, the opposite portion of the companion member having a projection over which one rope end lies, the other rope end adapted to pass slidingly through the trough and depression of the other member, and to be gripped therein by the portion of the other end of the rope 20 lying about the projection. 15

ANNA BAUER.
